ATTORNEY

UNITED STATES PATENT OFFICE.

FRANCIS G. HOWE, OF MELROSE, MASSACHUSETTS.

DESIGN FOR A BROOMHOLDER.

61,162.

Specification for Design.

Patented July 4, 1922.

Application filed July 1, 1921. Serial No. 481,953. Term of patent 14 years.

To all whom it may concern:

Be it known that I, FRANCIS G. HOWE, a citizen of the United States of America, residing at Melrose, in the county of Middlesex and State of Massachusetts, have invented a new, original, and ornamental Design for a Broom Holder, of which the following is a specification, reference being had to the accompanying drawing, forming a part thereof.

Fig. 1, is a front view of a broom holder showing my new design.

Fig. 2, is a side view thereof.

I claim:

The ornamental design for a broom holder, as shown.

In testimony whereof I affix my signature in presence of two witnesses.

FRANCIS G. HOWE.

Witnesses:

A. G. HOWE,

L. K. HALEY.
